(57) CLAIM

The ornamental design for a sports bag with a gear hook as shown and described.

DESCRIPTION

FIG. 1 is a front, top, and right side perspective view showing our new design.

FIG. 2 is a front view.

FIG. 3 is a back view.

FIG. 4 is a left side view.

FIG. 5 is a right side view.

FIG. 6 is a top view.

FIG. 7 is a bottom view.

FIG. 8 is an enlarged fragmentary perspective view of FIG. 1, showing the gear hook on the right side of the new design. FIG. 9 is an enlarged fragmentary rear perspective view showing the gear hook on the right side of the new design; and,

FIG. 10 is an enlarged fragmentary front perspective view showing the gear hook on the right side of the new design. The broken lines of the drawings indicate portions of the article that form no part of the claimed design.

1 Claim, 10 Drawing Sheets
